UNITED STATES PATENT OFFICE

WALTER V. ASH, OF PHILADELPHIA, PENNSYLVANIA

SUPPORT FOR CONNECTION CORDS OF ELECTRIC IRONS

Application filed June 4, 1929. Serial No. 368,209.

My invention relates to supports for the connection cords of electric irons, that is to say, to a device adapted to support such connection cords whereby the same will be held away from the articles being ironed, and also kept from becoming entangled during the various movements of the iron upon the ironing board or table.

The principal object of my invention is to provide a simple and efficient device for supporting the connection cord commonly used with an electric iron, whereby the cord will be kept free of entanglement, while at the same time perfect freedom in the use of the iron will be permitted.

A further object of my invention is to provide such a device which will be inexpensive in character, and which may be readily positioned when it is to be used.

20 The nature and characteristic features of my invention will be more readily understood from the following description, taken in connection with the accompanying drawings forming part hereof, in which:

25 Figure 1 is a perspective view of a device embodying the main features of my present invention, the same being shown in operative relationship with an electric iron, the cord for the same, and an ironing board upon which the iron is used;

Fig. 2 is an enlarged perspective view of the upper and lower portions of the device;

Fig. 3 is a side elevation, partly in section, of the lower portion of the device;

35 Fig. 4 is a perspective view of the upper portion of the device, the clamping member being removed for the purpose of better illustrating the peculiar shape of said upper portion;

40 Fig. 5 is a view similar to Fig. 1, of a modified form of the invention, so constructed and arranged as to be detachably mounted upon a wall of the room in which it is used;

Fig. 6 is an enlarged perspective view of 45 the upper and lower portions of the structure shown in Fig. 5;

Fig. 7 is a plan view of the lower portion of the structure shown in Fig. 5; and

Fig. 8 is a vertical section taken approximately on the line 8—8 of Fig. 7.

Referring now more particularly to Figs. 1 to 4 of the drawings, the device as there shown is adapted to be mounted upon the ironing board upon which the electric iron is to be used. For such attachment, the lower portion of the device comprises a spring clamp member 10, preferably made of a single piece of wire, and having two horizontal portions 11 adapted to engage the upper surface of the board, the wire being bent around at the rear ends of the horizontal portions 11 into another horizontal U-shaped extension 12, which is adapted to engage the under surface of the board.

The front ends of the horizontal portions 11 are bent toward each other, as at 13, being then bent upwardly, as at 14, where the same meet, to provide a support for a tubular member 15 which is mounted thereon.

The tubular member 15 has mounted in the upper portion thereof a coil spring 16, made of spring wire, preferably with the coils thereof closely wound and having such characteristics of resiliency that the coil spring 16 is normally maintained upright.

At the upper end of the coil spring 16, the wire of which is made extends forward horizontally, as at 17, being then bent and extending at right angles thereto in the same horizontal plane, as at 18, then being bent downwardly and extending vertically, as at 19, then being bent and extending horizontally, as at 20. At the end of the horizontal extension 20 the wire is bent upwardly, in a vertical direction, as at 21.

It should here be noted that the parts 18, 19, 20 and 21, at the front end of the horizontal extension 17 of the spring wire, all lie in the same vertical plane.

By the foregoing arrangement, the horizontal portion 20 serves as a pintle, upon which is mounted a spring clip 22 of a well known construction, the same preferably comprising two wooden members 23 and 24, held together by means of a spring 25, which is so arranged that when the upper ends of the members 23 and 24 are pressed toward each other, the jaws 26 and 27 will be separated.

The connection cord for the electric iron

is gripped between the jaws 26 and 27 at a suitable place along the length of the cord, so that the cord is held at all times above the surface of the ironing board.

5 It will be noted that as the electric iron is used, the coil spring 16 may be flexed in any desired direction, so as to permit the utmost freedom of the iron, but when the tension on the same is released, the coil spring 16 will return to its normal upright position.

10 It will also be noted that the spring clip 22, while free to move axially upon the projecting portion of the coil spring upon which it is mounted, will, however, be prevented 15 from becoming accidentally detached therefrom, by reason of the vertical extensions 19 and 21, which serve to maintain it in the proper position at the forward end of the horizontal arm 19 provided at the upper end 20 of the coil spring.

25 It will also be noted that the connection cord will be secured in the spring clip 22 in such manner that there is no likelihood of the same becoming entangled with any portion of the support.

30 In Figs. 5 to 8 of the drawings, there is shown a modified form of the invention, in which the coil spring 16 is supported in a portion 30 of a plate bracket 31, which extends angularly as at 32, and vertically as at 33.

35 The vertically extending portion 33 of the bracket 31 is adapted to be seated in a pocket portion 34 of a wall plate 35. The wall plate 35 may be secured by screws 36, or any other suitable fastening means, to the wall of the room in which the electric iron is used.

40 It will be seen that there is thus provided a simple, inexpensive, and efficient device for 45 supporting the connection cords of electric irons, which is so constructed and arranged as effectively to prevent entangling of the cord, which will keep the same away from the articles being ironed, and in which likelihood of the cord becoming entangled in the support is eliminated.

I claim:

50 In a device for supporting the connection cords of electric irons and the like, a closely wound coil spring normally maintained in an upright position, a spring clip for securing the connection cord carried at the upper end of said coil spring, the support for said spring clip comprising an integral extension of the 55 wire of which the coil spring is made, said extension projecting forwardly in a horizontal direction, and being then bent to provide a horizontal portion upon which the spring clip is pivotally mounted and portions at 60 right angles to said horizontal portion between which the spring clip is positioned.

65 In testimony whereof, I have hereunto signed my name.

WALTER V. ASH.
